NC (US)

CLAIM

(**) Term: **14 Years**

The ornamental design for a faceplate for a wall-mount
distributed filter housing, as shown and described.

(21) Appl. No.: **29/127,805**

DESCRIPTION

(22) Filed: **Aug. 11, 2000**

FIG. 1 is a front perspective view of an embodiment of a
faceplate for a wall-mount distributed filter housing according
to our new design;

(51) LOC (7) Cl. **11-05**

FIG. 2 is a top plan view thereof;

(52) U.S. Cl. **D8/353**

FIG. 3 is a front elevation view thereof;

(58) Field of Search D13/177; D8/350-353;
220/241; 174/66; 16/402

FIG. 4 is a bottom plan view thereof;
FIG. 5 right side elevation view thereof; and,
FIG. 6 is a left side elevation view thereof.

(56) **References Cited**

The broken lines in FIG. 1 illustrating possible internal
components and mounting hardware are for illustrative
purposes only and form no part of the claimed invention.
FIGS. 2-6 are shown on a reduced scale.
